**APPARATUS FOR CRUSHING ROCK OR THE LIKE
INCLUDING A SWINGING BREAKER BAR**

Albert B. Hanss and Leonard N. Kint, Cedar Rapids, Iowa, assignors to Pettibone Mulliken Corporation, a corporation of Delaware

Filed June 15, 1962, Ser. No. 202,868

5 Claims. (Cl. 241—189)

The present invention relates to an apparatus for crushing rock or the like and includes a swinging breaker bar. 10

Rock crushers of the type employing a rotor or impeller rotating about a horizontal axis have been used with various types of impacting structures against which the rock is thrown by the impeller. Impacting structures 15 which are mounted in a fixed position have the disadvantage that there are limitations as to how close they may be set to the impeller. If they are set too close to the impeller, there will be occasional pieces of rock which are not fractured and which will be sufficiently large to 20 be trapped between the impacting face and the impeller. When so trapped they are likely to result in excessive wear or damage to the crushing apparatus. As a consequence, it has been necessary to space the impacting structure a distance from the impeller sufficiently enough to permit 25 any such uncrushed pieces of rock to pass on out of the machine rather than being trapped therein. With such spacing, other pieces of rock which would be crushed where they strike the impacting structure will pass between the impacting structure and the impeller. In so 30 doing they either will fail to be crushed at all or they will impact against other portions of the structure which are not intended or protected for that purpose and will be damaged by the impact.

In an effort to overcome the foregoing disadvantages some rock crushers have employed pivotally mounted impacting faces. The theory has been that the impacting face could be positioned sufficiently close to the impeller so that all of the rock thrown would be directed 40 at the impacting face. At the same time, should a piece of rock fail to be crushed it would push the face back out of the way and permit the piece of rock to pass on out of the machine. While a device of this type overcomes the problem previously mentioned, it introduces other difficulties.

The frame or casing of the apparatus within which the impeller and the impacting device are located, necessarily must be extremely sturdy to withstand the blows and forces applied to it as rock is crushed. The side walls between which the impeller and the impacting device extend must be extremely rigid to withstand the blows and forces applied to them. With a swinging impacting device, it is virtually impossible to provide adequate internal bracing for these side walls with the result that either the casing must be made substantially more rigid by external construction or it is likely to be distorted and damaged during the use of the apparatus.

We have devised a structure wherein a fixed impacting device is employed. The fixed impacting device being secured to the two side walls supplies a rigid internal bracing for the side walls. Thus the external structure for supporting these walls need not be as rigid as would otherwise be the case. The size and positioning of the fixed breaker device is such that a space is provided between it and the impeller sufficient to permit uncrushed pieces of rock to pass therethrough without impact. The pivotal mounting and mass of this swinging impacting device are such that the blow between it and any rock will normally be sufficient to crush the

2

rock. If a piece of rock is not crushed upon impacting with either the fixed face or the pivotal device, as the case may be, it will push the swinging breaker device out of the way so that it can pass from the machine.

While the pivoted impacting device has sufficient inertia to resist the rock crushing blows and not be pushed back by the normal impacting of rock thereagainst, it is possible that it can be pushed out of the way more easily when an uncrushed rock is pushed against it by the rotor than can be the swinging impacting devices of the prior art. In the prior art devices the swinging impacting structures were much larger and more massive since they formed the principal impacting device of the apparatus. As a consequence, more force was required to open them to permit an uncrushed rock to exit with the greater likelihood of damage to the apparatus before the rock would exit. Furthermore, usually they were hook-shaped which might make them difficult to open to let trapped rock out under some circumstances. In the device of our invention the principal impacting face (in addition to the rotor) is that on the fixed impacting device. The swinging impacting device is in the nature of a supplementary apparatus and it will open and close more rapidly in response to the pushing forces of uncrushed rocks shoved against it by the impeller.

Another advantage of our invention is that it readily may be added to existing crushers presently in use without substantial modifications thereof. Many of the present crushers inherently have a structure into which our invention may be incorporated. In such a case it is a relatively simple matter merely to position the swinging impacting device in place and secure the pivotal connections therefor to the present structures.

Further objects and advantages will become apparent 35 from the following description taken in conjunction with the drawings in which:

FIGURE 1 is an elevation of a rock crusher embodying our invention illustrated in section;

FIGURE 2 is a view corresponding to FIGURE 1 illustrating the normal position of the swinging breaker bar; and

FIGURE 3 is a view at line 3—3 of FIGURE 2.

Although the following disclosure offered for public dissemination is detailed to ensure adequacy and aid understanding, this is not intended to prejudice that purpose of a patent which is to cover each new inventive concept therein no matter how others may later disguise it by variations in form or additions or further improvements. The claims at the end hereof are intended as 50 the chief aid toward this purpose; as it is these that meet the requirement of pointing out the parts, improvements, or combinations in which the inventive concepts are found.

The illustrated apparatus comprises a casing generally 55 10 which serves as a frame for the machine. Casing 10 comprises two side walls 11, a top wall 12, a back wall 13 and a bottom 14. Bottom 14 has an opening 15 through which the crushed rock is discharged. The rock to be crushed is fed in through a chute 16, or by other suitable means.

An impeller or rotor generally 18 is positioned between side walls 11. It has shafts, not shown, suitably journaled in frame 10 for rotation about the axis 19 of the rotor. Rotor 18 has a plurality of hammers 20 spaced about the periphery of the rotor and extending parallel to axis 19. Hammers 20 project from the periphery of the rotor. They are releasably mounted in place as by means of wedges 21 so that they may be removed and replaced when wear has occurred. The rotor has two end plates 60 22 between which the hammers extend.

Rotor 18 is connected to a suitable power means, not

shown, which rotates the rotor in the direction indicated by arrow 24. As the rock descends onto the rotor from chute 16 an impact occurs between the rock and one of hammers 20. Some of the rock is broken at this time. The rock, broken or unbroken by the hammers, is thrown generally upward and to the right as viewed in FIGURE 1. A large portion of the rock so directed will impact against the fixed grate 25. Grate 25 is secured to the two side walls 11, as by means of bolts 26. Grate 25 is defined by a plurality of spaced vertical bars 27 and cross bars 28-31. If the rock is sufficiently small it will pass between the vertical bars 27 in the spaces 32.

A swinging breaker bar assembly 35 is pivotally attached to fixed grate 25. Breaker bar 35 includes an upper pair of generally horizontal arms 36 attached to a pair of depending arms 37. The two attached arms of each pair is of a generally L-shaped configuration. One end of each of arms 36 is journaled on a rod 38 affixed to fixed grate 25 as by means of welding. A face plate 39 and supports 40 are secured to the lower ends of each of arms 37. A wear plate 41 is held in place by a plurality of bolts 42. Support 40, and plates 39 and 41 jointly form a breaker bar. At one end bolts 42 are threaded into wear plate 41, the bolts then extend through suitable openings in face plate 39 and between supports 40. Washers 43 bridge supports 40 with nuts 44 being tightened against the washers.

In normal operation the swinging breaker bar assembly 35 hangs in the position illustrated in FIGURE 2. In this position, its breaker bar 39, 40, 41 is relatively close to the path of movement of hammers 20 as illustrated in FIGURE 2. Because of this position it is often called a stripper. The exact size of its spacing from the hammer circle will depend upon the preferences of the user. The smaller it is made, the greater will be the percentage of relatively small dimension material in the crushed rock. The weight of this breaker bar, particularly as that weight is concentrated in the two plates 39 and 41 and supports 40, coupled with the positioning thereof with respect to the pivotal axis defined by rods 38, acts to normally hold the breaker bar in the FIGURE 2 position. As seen in FIG. 2, the rear edge of bottom grate bar 31 acts as a stop against which arms 37 are pressed by gravity. As rock is thrown against the wear plate 41 the breaker bar will tend to maintain the FIGURE 2 position and serve as a rock crushing element.

However, should a piece of relatively unbreakable material larger than the dimension between the hammer 20 and plate 41 of FIGURE 2 become wedged between a hammer 20 and the breaker bar 35, the breaker bar can be pushed back to permit the rock to be ejected from the machine as illustrated in FIGURE 1. As soon as the rock has passed between the hammer and the breaker bar, the swinging breaker bar will again swing down to the FIGURE 2 position to effectively serve as a rock crushing element. Primarily the rock is crushed either by impact against the hammers 20 or against the fixed grate 25. However, the swinging breaker bar 35 serves as a supplemental impacting member and in addition serves to retain rock in the working zone until it has been reduced in size to substantially the desired extent. It will also be noted that the fixed grate 25 serves as an internal brace between walls 11 of the casing.

The term "rock" as used herein is employed to not only apply to natural stone, but also to such other materials of similar characteristics which one might wish to crush in a machine of the general type described. An example of such other material would be slag.

Breaker bar 35 may be made in several sections each mounted on separate arms. In that event one section may be pushed back to permit a large relatively unbreakable object to go through without disturbing the remainder of the sections. The remaining sections continue their normal function of serving as an impacting member and

retaining the rock in the active zone until reduced to the desired size.

We claim:

1. An apparatus for crushing rock or the like including: 5 a casing having a pair of generally parallel side walls; an impeller mounted in said casing for rotation about a generally horizontal axis intersecting said side walls, and driven in a given direction, means to feed rock toward the upper side of said impeller at a zone from which it will be thrown both upwardly and in said given direction; 10 a fixed grate device secured to said walls and extending therebetween, said device having an impacting face above and generally in said direction from said axis with its bottom terminus being spaced from the impeller whereby part of the rock would pass through the space between the impeller and the face, said grate device having openings therethrough; arm means pivotally mounted in front of said grate device and extending approximately horizontally through said openings; depending support means attached to the arm means in said direction 15 from said device and extending downwardly from the arm means; and a breaker member affixed to the bottom portions of the support means and positioned to intercept said part of the rock or the like, said member being in said direction from the pivotal connection and at a lower elevation than the pivotal connection.

2. An apparatus as set forth in claim 1, wherein the face slopes downwardly with the bottom of the face being in said direction from the top of the face, said 30 openings in said face are vertically elongated slots, said arm means comprise two approximately L-shaped arms having an upper part and a lower part, said upper parts extending through said slots from the rear of the face with the forward ends being pivotally connected to the frame in front of the face, said lower parts extending downwardly from the upper parts rearwardly of said face, the bottom ends of the lower parts being attached to the member, said member having an impacting face angled upwardly in said direction; and a fixed stop device abutting said means to prevent downward pivotal movement of the arm means.

3. In an apparatus for crushing rock or the like comprising a frame including a casing having a pair of generally parallel side walls, an impact hammer rotor extending between the side walls and driven in a given direction, means for feeding rock to an impact zone adjacent the part of the rotor approaching the top thereof to be fractured thereby and thrown generally in said direction, a fixed screen device secured to said walls and extending therebetween in an upstanding position for intercepting oversize rock and rebounding it in the reverse direction, said casing forming a downwardly extending passage from the rear side of the screen through which the sized rock passing through the screen device falls to discharge, the improvement including: a breaker bar positioned as an extension of the screen device toward the rotor to intercept oversize rock passing under the screen device, and including mounting means pivotally connecting said member to said frame, the pivotal connection being above and in the reverse of said direction from said member whereby the weight of the member urges the member to said position and the member will swing away from the impeller when sufficient force is applied to the member to overcome said urging; said apparatus including stop means to prevent the pivoting of the member toward the impeller beyond said position.

4. In an apparatus for crushing rock or the like comprising a frame including a casing having a pair of generally parallel side walls, an impact hammer rotor extending between the side walls and driven in a given direction, means for feeding rock to an impact zone adjacent the part of the rotor approaching the top thereof to be fractured thereby and thrown generally in said direction, a fixed screen device secured to said walls and

extending therebetween in an upstanding position for intercepting oversize rock and rebounding it in the reverse direction, said casing forming a downwardly extending passage from the rear side of the screen through which the sized rock passing through the screen device falls to discharge, the improvement including: a breaker bar positioned as an extension of the screen device toward the rotor to intercept oversize rock passing under the screen device, and including mounting means pivotally connecting said member to said frame, the pivotal connection being above and in the reverse of said direction from said member whereby the weight of the member urges the member to said position and the member will swing away from the impeller when sufficient force is applied to the member to overcome said urging; said apparatus including stop means to prevent the pivoting of the member toward the impeller beyond said position, the entire of said stripper member being located remotely from the axis of said pivotal connection.

5. In an apparatus for crushing rock or the like comprising a frame including a casing having a pair of generally parallel side walls, an impact hammer rotor extending between the side walls and driven in a given direction, means for feeding rock to an impact zone adjacent the part of the rotor approaching the top thereof to be fractured thereby and thrown generally in said direction, a fixed screen device secured to said walls and extending therebetween in an upstanding position for intercepting oversize rock and rebounding it in the reverse direction, said screen extending across a substantial part of the path

20

25

30

of fragments thrown from the impact zone but leaving a space next to the rotor through which oversize relatively unbreakable bodies can pass, said casing forming a downwardly extending passage from the rear side of the screen through which the sized rock passing through the screen device falls to discharge, the improvement including: a breaker bar positioned as an extension of the screen device toward the rotor to intercept oversize rock passing under the screen device, and including mounting means pivotally connecting said member to said frame, the pivotal connection being above and in the reverse of said direction from said member whereby the weight of the member urges the member to said position and the member will swing away from the impeller when sufficient force is applied to the member to overcome said urging; said apparatus including stop means to prevent the pivoting of the member toward the impeller beyond said position.
